UNITED STATES PATENT OFFICE

1,925,684

CARBURETOR FIRE BAFFLE

Rudolph J. Anschicks, Chicago, Ill., assignor to
Protectoseal Company of America, Chicago,
Ill., a corporation of Illinois

Application August 24, 1929. Serial No. 388,158

1 Claim. (Cl. 123—142)

My invention relates to carburetors, and more particularly, it relates to improved closure means for the air inlet of a carburetor which operates as a fire baffle to extinguish flames and a muffler for explosive noises incidental to what is known as back firing.

An object of the invention is the provision of improved fire baffle construction in combination with the air inlet of a carburetor which is operable to prevent exterior conflagration in the event of back firing from the carburetor.

Another object of the invention is the provision of improved fire baffle construction mounted in the air inlet of a carburetor so as to permit unrestricted flow of air into the carburetor and to prevent the escape of back fire flames from the interior of the carburetor through the air inlet.

Still another particular object of the invention is the provision of an improved device operable as a fire baffle and capable of being installed in the main air inlet of a carburetor and which also acts as a muffler to deaden the explosive noises incidental to such back fire explosions.

Another object of the invention is the provision of a device of the kind described in combination with a carburetor which is simple, compact, durable, reliable, efficient, and satisfactory for its intended purpose.

Many other objects and advantages of the construction herein described and shown will be obvious to those skilled in the art from the disclosure herein given.

To this end my invention consists in the novel construction, arrangement and combination of parts herein described and shown and more particularly pointed out in the claim.

Referring now to the drawing forming a part of this specification:

Fig. 1 is an elevational view showing a carburetor diagrammatically as attached to an automobile engine and having the device of my invention mounted thereon;

Fig. 2 is a section along the line 2—2 of Fig. 1, drawn to a larger scale; and

Fig. 3 is a view along the line 3—3 of Fig. 1, drawn to a larger scale.

Referring now more particularly to the drawing, the numeral 10 generally designates a carburetor used in connection with a gas engine. The carburetor comprises an air inlet pipe 11 opening into a mixing chamber 13 and a gas inlet 12 opening into a float chamber 14.

The carburetor parts are shown diagrammatically, inasmuch as the invention resides in the

combination of my improved fire baffle, generally designated by the numeral 29, with a carburetor, the baffle being operable to control the air inlet pipe 11 of the carburetor. The float chamber 14 is fastened to the main body of the carburetor by a plurality of bolts 20. The mixing chamber 13 discharges into a mixture pipe 15 forming the upper portion of the carburetor. The mixture pipe 15 opens into a pipe 16, leading to the engine which is supplied by the carburetor. The pipes 15 and 16 are provided with flanges 17 and 18, respectively. The flanges 17 and 18 form a fluid tight joint and are held or fastened together by a plurality of bolts 19.

The construction shown is typical of any carburetor of the general class described, wherein, by reason of a lean mixture of air and gas, there is incomplete combustion in the engine cylinder, and an explosive back fire through the inlet pipe 11 results. The escape of such a back fire frequently results in the ignition of combustible gases and gas or oil drippings that accumulate about or underneath the engine, thereby causing an undesirable and sometimes dangerous conflagration. Such combustion of the gas and drippings about the engine is avoided and the loud explosive noises incidental to such back fire prevented by mounting my combination fire baffle and muffler 29 in the air inlet pipe 11. The fire baffle 29 is similar in construction to the apparatus shown and described in my copending applications, Serial #305,088, filed September 10, 1928, and Serial #354,329 filed April 11, 1929.

The baffle 29 comprises a pipe section 21, finished to form a close fit with the interior of the inlet pipe 11. A plurality of slots 22 are formed in the side walls of the pipe section 21 to make it easy to insert the closely fitting section in the air inlet pipe 11. The outer end of the pipe section 21 is provided with a flange 23.

In addition to the ring 21 and the flange 23, the fire baffle comprises an outer disk cover 28, of the same outer diameter, preferably, as that of the flange 23. Between the disk cover 28 and the flange 23 are positioned a plurality of annular plates 24. The plates 24 are preferably of the same width as the flange 23, so that the inner width or cross-sectional area of the space enclosed by the plates corresponds to the opening through the pipe 21. A plurality of washers 25 are positioned between the flange 23 and the adjacent plate 24 and between the disk cover 28 and the adjacent plate 24, as well as between each of the other plates 24. The washers 25 serve to keep the plates 24 an equal distance

apart, so that between each two of the annular plates a ring or slit-like opening 26, of the thickness of the washers is formed. All of the washers 25, the plates 24 and the disk cover 28 are held together and fastened to the flange 23 by means of bolts 27, so that the ring, or slit-like openings 26 cannot be altered.

The total area of the openings 26 should be at least as large as the size of the opening through 10 the pipe section 21, thereby permitting air to enter the carburetor without hindrance. The slit-like openings 26 are made relatively thin so that it is impossible for the flame burning outwardly in the event of back fire to penetrate 15 through the openings between the rings on account of the thickness of the openings and the distance the flame has to pass in consequence of the width of the plates 24. The burning gases in passing between the plates 24 are cooled sufficiently to extinguish the flame. Since the openings between the various plates 24 are equal in area to the opening through the pipe, the baffle presents little or no resistance to the escape of 20 gases during back firing while at the same time 25 functioning as a flame extinguisher.

The fire baffle 29 also operates as a muffler for the carburetor in the case of back fires or explosions for the reason that both the escaping gases and the inrushing air must pass through 30 the plurality of spaces 26, rather than through one single opening.

Thus, it will be seen that I have provided a device suitable for mounting in combination with

any typical carburetor for gas engines which serves as a fire baffle to prevent propagation of fire outwardly from the carburetor and also as a muffler to subdue the loud noises and reports which are incidental to the back firing of the 80 carburetor through an open air inlet.

Having thus described my invention, it is obvious that various immaterial modifications may be made in the same without departing from the spirit of my invention; hence, I do not wish to be understood as limiting myself to the exact form, construction, arrangement and combination of parts herein described and shown, or uses 85 mentioned.

What I claim as new and desire to secure by Letters Patent is:

A device providing a fire baffle adapted for mounting in an air intake pipe of a carburetor, 90 said device comprising a flange member having an annular collar closely fitting the carburetor intake pipe, a circular plate in spaced apart relation to said flange member, a plurality of annular rings arranged in closely spaced relation between said plate and flange, means for holding said flange member, plate and rings in assembled 95 position, and means holding said rings in sufficiently closely spaced relation that spark and flame laden gases accompanying backfiring are quenched upon passing therethrough, the number of said spaces being such that their total area 100 is not less than the cross sectional area of the carburetor intake pipe.
